UNITED STATES PATENT OFFICE.

THOMAS B. FAGAN, OF VANWERT, OHIO.

DESIGN FOR A WINDROWER FOR MOWING-MACHINES.

SPECIFICATION forming part of Design No. 35,191, dated October 15, 1901.

Application filed August 23, 1901. Serial No. 73,102. Term of patent 14 years.

To all whom it may concern:

Be it known that I, THOMAS B. FAGAN, a citizen of the United States, residing at Van Wert, in the county of Van Wert and State of Ohio, have invented and produced a new and original Design for a Windrower for Mowing-Machines, of which the following is a specification, reference being had to the accompanying drawings, forming part thereof.

The figure is a top plan view of the windrower.

As shown in the drawing, the leading or material feature of my design consists of a series of parallel slats of gradually-increasing length, each slat being flat or of much greater

width than thickness and each turned up at the rear with a gradually-curved hook-shaped end *a* and each hooked end having the plane of its terminal portion twisted, so that said plane stands at an oblique angle to the longitudinal axis of the straight body part. 20

Having thus described my invention, what I claim as new, and desire to secure by Letters Patent, is—

The design for a windrower for mowing- 25 machines as herein shown and described.

THOMAS B. FAGAN.
